ATTORNEY.

UNITED STATES PATENT OFFICE.

CLARK W. MCKEE, OF SAN DIEGO, CALIFORNIA.

GRAVITY-ACTUATED WINDOW-LOCK.

1,032,559.

Specification of Letters Patent. Patented July 16, 1912.

Application filed February 6, 1911, Serial No. 606,789. Renewed May 22, 1912. Serial No. 699,070.

To all whom it may concern:

Be it known that I, CLARK W. MCKEE, a citizen of the United States, and a resident of San Diego, in the county of San Diego 5 and State of California, have invented certain new and useful Improvements in Gravity-Actuated Window-Locks, of which the following is a specification.

My invention relates to a gravity actuated window lock and the objects are, to provide a simple, economically constructed and easily installed lock for window sashes, and more particularly one that will automatically lock the two sashes together when 15 the window is closed or nearly closed.

My invention is applicable to and may be fitted to any window sashes, and it can be placed on the sashes so that the window may be securely locked and at the same time be 20 open at the top or bottom to allow for ventilation.

With these and other objects in view, as will appear hereinafter, my invention consists of certain novel features of construction, combination and arrangement of parts 25 as will be described in detail and particularly set forth in the appended claim, reference being had to the accompanying drawings, and to the characters of reference 30 thereon, which form a part of this specification, in which:

Figure 1 is an elevational view of two window sashes in their relative positions showing the locks in position thereon and the window closed, Fig. 2 is a side elevational view thereof, Fig. 3 is a front elevational view of the part attached to the upper sash, Fig. 4 is a side elevational view thereof, showing the different positions of the 35 latch by dotted lines, Fig. 5 is a top view thereof, Fig. 6 is a sectional view of the plate portion locking in one direction, Fig. 7 is a sectional view of the same looking in the opposite direction, Fig. 8 is a side elevational view of the latch, Fig. 9 is an elevational view of the same at right angles to Fig. 8, Fig. 10 is a top view thereof, and Fig. 11 shows the bearing plate which is to 40 be attached to the lower sash.

Similar characters of reference refer to similar parts throughout the several views.

My lock consists of plate 1, latch 2, catch 3, and bearing plate 4. Plate 1 is rectangular shaped and of a suitable size to be fitted 45 into the side of a window sash and is provided with holes 1^a into which screws are

inserted for attaching it to the window sash,—enough material being cut out of the sash to provide a space in which the latch 2 may swing as shown best in Fig. 4. Plate 1 is shaped as shown best in Figs. 4, 5, 6, and 7 and is provided on its sides with inwardly extending webs 1^b and 1^c. In web 1^b is provided a downwardly extending groove 1^d adapted for the pivot lug 2^b of the 60 latch 2, while in the web 1^c is provided a hole adapted for the pivot lug 2^c, so that in order to insert the latch into the plate, the lug 2^c is placed in the hole in web 1^c, and the lug 2^b passes downwardly through groove 70 1^d to its position in web 1^b as shown. In each side of the plate 1 is provided a recess 1^e, which is provided with a horizontally threaded hole. In this recess, and pivoted upon a screw 3^a, screwed into the hole in 75 said recess, is pivotally mounted catch 3 which is gravity actuated.

The latch 2 is shaped as shown best in Fig. 8, and its heavier portion is near the top and extended from the pivoted point, thus 80 facilitating its gravity action. The lower and inner portions are hollowed out at 2^a. This latch is provided with pivot lugs 2^b and 2^c which are respectively adapted for the hole in web 1^c, and groove 1^d in web 1^b. 85 The latch is also provided with a slot 2^d adapted to receive a corner of the catch 3, when it is in the proper relative position thereto. Latch 2 is also provided with a stop 2^e on its lower end adapted to prevent 90 its swinging outwardly too far. On the lower sash, plate 4 is placed in a position to engage with the lower surface of the latch 2 and the member 4^a is shaped to conform to the surface of the lower end of said latch 95 2, and it is attached to the lower sash by means of screws in screw holes 4^b.

In Fig. 1, I have shown the device on one side of the window attached to the upper sash in a position to lock the window when 100 closed, while on the other side I have shown it placed so that it will allow the upper sash to be lowered or raised some and still be securely locked.

It will be readily seen that with this construction and arrangement, there is provided a good and substantial lock adapted to lock the two sashes of a window in their relative positions as desired, that the parts are very simple of construction and are easily installed in the sashes.

Having thus described my invention, what

I claim as new and desire to secure by Letters Patent is:—

A gravity actuated window lock, comprising a plate embedded in and attached to an upper window sash, provided with inwardly extending webs provided with a hole in one and a groove in the other, a readily detachable latch pivotally mounted thereon in said hole and groove and provided with a slot in its lower portion, the lower surface of said latch being concentric with the pivot point, a pivotally mounted gravity actuated catch set in a recess in said plate adapted to engage in said slot and hold said latch in

its operative position and to engage the outer surface of said latch to hold said latch in its inoperative position, and a curved plate on the lower sash adapted to engage with said latch and to conform to the lower surface thereof, all substantially as set forth. 20

In testimony whereof, I hereunto set my hand in the presence of two subscribing witnesses.

CLARK W. MCKEE.
